ASH RECEIVER

Walter von Nessen, New York, N. Y., assignor to
The Chase Companies, Incorporated, Water-
bury, Conn., a corporation

Application October 2, 1934, Serial No. 746,535

9 Claims. (Cl. 131—51)

This invention relates to an improvement in 5
ash receivers for smokers' use and particularly
to that class of ash receivers having tiltable
members for delivering or conveying ashes, etc.,
into interior receiving-chambers.

One of the objects of the present invention
is to provide a superior ash receiver character-
ized by its provision with means for readily and
conveniently removing deposited ashes from
10 sight.

A further object is to provide a superior ash
receiver having simple and effective means for
minimizing the escape of smoke and fumes from
its interior.

15 Other objects and advantages will appear to
those skilled in the art from the following, con-
sidered in conjunction with the accompanying
drawing and the appended claims.

In the accompanying drawing:

20 Fig. 1 is a view in side elevation of one form
which an ash receiver may assume in accordance
with the present invention;

Fig. 2 is a top or plan view thereof;

25 Fig. 3 is a broken transverse sectional view
taken on the line 3—3 of Fig. 2;

Fig. 4 is a view in side elevation of the top
or cover member of the body, detached; and

Fig. 5 is a perspective view of one of the tilt-
able troughs, detached.

30 The particular ash receiver herein chosen as
illustrative of the present invention includes a
hollow body generally designated by the refer-
ence character 10 and comprising a lower mem-
ber 11 and a top or cover member 12. The top
35 member 12 just referred to is expanded at its
lower end as at 13 in order to be slipped over
the upper end of the lower member 11. The
expanded lower end 13 of the cover member 12
is provided at three (more or less) equidistant
40 points with indent 14, each of which is adapted
to be engaged with an L-shaped groove 15, three
of which latter are indented from the periphery
of the lower member 11 adjacent the upper end
thereof. Each L-shaped groove just described,
45 together with its complementary indent 14, pro-
vides in effect a so-called "bayonet" lock.

Preferably, the upper portion of the top or
cover member 12 is contracted as shown to pro-
vide what for convenience may be described as
50 a "smoke-dome" 16 and is provided below the
said dome with three (more or less) laterally-
opening passages or slits 17 preferably spaced
equidistantly around the circumference of the
member 12 and each of U-shaped form when
55 viewed from the side of the body. The U-shaped

form of the slits 17 provides, between the ver-
tical legs of each thereof, a downwardly-extend-
ing guard-tongue 18, each of which projects into
and coats with a tiltable trough 19 in a manner
as will more fully hereinafter appear.

Each of the tiltable troughs 19 is of U-shaped
form in cross-section and has its inner end ex-
tending inwardly into the interior of the body
10 through one of the complementary U-shaped
slits 17. Intermediate its inner and outer ends,
10 each of the troughs 19 is tiltably attached to
the top or cover member 12 by means of a hinge
20 or equivalent pivoting means. Each of the
hinges 20 is preferably so located lengthwise of
its complementary trough 19 as to cause the
outer end of the said trough to overbalance the
inner end thereof, so that the inner end of the
trough is normally held upwardly, with its upper
15 face in engagement with the lower edge of the
guard-tongue 18, which latter thus serves to limit
the downward tilting of the outer end of the
trough in question.

Each of the troughs 19 provides a convenient
20 temporary receptacle for the deposit of cigar
and cigarette ashes, etc., or as a temporary rest-
ing place for a cigar or cigarette such as 21, as
indicated in Fig. 1. When it is desired to remove
25 from sight the ashes, cigarette stubs, etc., previ-
ously deposited in one of the troughs 19, this
may be accomplished by lifting upwardly upon
the outer end of the trough to swing the latter
30 into the position indicated by dotted lines in Fig.
3, whereupon the material contained in the trough
will fall into the interior of the body 10.

When the trough is again restored to the posi-
tion in which it is shown in full lines, the guard-
tongue 18, reaching down, as it does, into the in-
terior of the trough, will serve to substantially
35 prevent, or at least minimize, the escape of ob-
jectionable odors, smoke, etc., from unextin-
guished cigar or cigarette stubs contained in the
interior of the body 10. The prevention of the
40 escape of smoke, etc., from the interior of the
body is facilitated by the fact that there is with-
in the smoke-dome 16 a space above the slits 17
45 in which the smoke may collect without exerting
any appreciable tendency to escape laterally.

As before described, each tiltable trough is so
hinged that when once restored to its normal
50 horizontal position its outer end overbalances its
inner end to thus maintain the trough in such
position with the upper face of its inner end
engaged with the lower edge of a complementary
guard-tongue 18. The said guard-tongue also
55 serves to prevent a bystander from looking into

the soiled interior of the body 10, and further imparts to the device an attractive and finished appearance.

5 The ash receiver herein illustrated is equipped with three corresponding tilttable troughs, though it is obvious that only one need be employed in a basic structure.

10 The invention may be carried out in other specific ways than that herein set forth without departing from the spirit and essential characteristics of the invention, and the present embodiment is, therefore, to be considered in all respects as illustrative and not restrictive, and all changes coming within the meaning and equivalency range of the appended claims are intended to be embraced therein.

I claim:

20 1. An ash receiver including in combination a hollow body having a lateral passage therein; a vertically-tiltable trough pivotally supported intermediate its respective opposite ends by the said body and having its inner end projecting into the interior of the said hollow body through the lateral passage therein; and a depending guard-tongue carried by the said body and projecting downwardly into the said tilttable trough at a position intermediate the pivot-point thereof and the interior of the said hollow body.

30 2. An ash receiver including in combination a hollow body surmounted by a smoke-dome and having a lateral passage therein located in a plane below the top of the said smoke-dome; a vertically-tiltable trough pivotally supported intermediate its respective opposite ends by the said body and having its inner end projecting into the interior of the latter through the aforesaid lateral passage therein; and a guard-tongue depending from the smoke-dome portion of the body and projecting downwardly into the said tilttable trough at a position intermediate the pivot-point thereof and the interior of the said hollow body.

40 3. An ash receiver including in combination a hollow body surmounted by a smoke-dome and having a lateral passage therein located in a plane below the top of the said smoke-dome; a vertically-tiltable trough pivotally supported intermediate its respective opposite ends by the said body and having its inner end projecting into the interior of the latter through the lateral passage therein; and a depending guard-tongue formed integral with the wall of the smoke-dome portion of the said body and projecting downwardly into the said tilttable trough at a position intermediate the pivot-point thereof and the interior of the said hollow body.

50 4. An ash receiver including in combination a hollow body having a lateral passage therein; a vertically-tiltable trough pivotally supported intermediate its respective opposite ends by the said body and having its inner end projecting into the interior thereof through the lateral passage therein; and a depending guard-tongue carried by the said body and projecting downwardly into the said tilttable trough at a position intermediate the pivot-point thereof and the interior of the said hollow body; the said vertically-tiltable trough having a major portion of its weight positioned outwardly with respect to its pivot-point to thus normally maintain its inner end in engagement with the said guard-tongue.

5 5. An ash receiver including in combination a hollow body having a plurality of lateral passages opening through its wall; a plurality of vertically-tiltable troughs respectively extending through the lateral passages of the said body and each trough being pivotally supported intermediate its respective opposite ends by the body; and a plurality of depending guard-tongues carried by the said body and each projecting downwardly into one of the said tilttable troughs at a position intermediate the pivot-point thereof and the interior of the said hollow body.

10 6. An ash receiver including in combination a hollow body comprising upper and lower complementary separable members, the said upper member being provided with a lateral passage; a vertically-tiltable trough pivotally supported intermediate its respective opposite ends by the upper member of the said body and having its inner end projecting into the interior thereof through the lateral passage therein; and a depending guard-tongue carried by the upper member of the said body and projecting downwardly into the said tilttable trough at a position intermediate the pivot-point thereof and the interior of the said hollow body.

15 7. An ash receiver including in combination a hollow body comprising upper and lower complementary separable members, the said upper member being provided with a lateral passage; a vertically-tiltable trough pivotally supported intermediate its respective opposite ends by the upper member of the said body and having its inner end projecting into the interior thereof through the lateral passage therein; and a depending guard-tongue carried by the upper member of the said body and projecting downwardly into the said tilttable trough at a position intermediate the pivot-point thereof and the interior of the said hollow body; the said vertically-tiltable trough having a major portion of its weight positioned outwardly with respect to its pivot-point to thus normally maintain its inner end in engagement with the said guard-tongue.

20 8. An ash receiver including in combination a hollow body comprising upper and lower complementary separable members, the said upper member being provided with a lateral passage; a vertically-tiltable trough pivotally supported intermediate its respective opposite ends by the said body and having its inner end projecting into the interior thereof through the lateral passage therein; and a depending guard-tongue formed integral with the wall of the upper member of the body and projecting downwardly into the said tilttable trough at a position intermediate the pivot-point thereof and the interior of the said hollow body.

25 9. An ash receiver including in combination a hollow body having a U-shaped lateral passage therein; a vertically-tiltable trough pivotally supported intermediate its respective opposite ends by the said body and having its inner end shaped for passage inwardly through the U-shaped lateral passage in the said body; and a depending guard-tongue carried by the said body and projecting downwardly into the said tilttable trough at a position intermediate the pivot-point thereof and the interior of the said hollow body.
